UNITED STATES PATENT OFFICE.

JAN KULHÁNEK, OF PRAGUE, AUSTRIA-HUNGARY.

PROVISIONAL OR PERMANENT WALL.

SPECIFICATION forming part of Letters Patent No. 728,472, dated May 19, 1903.

Application filed October 13, 1902. Serial No. 127,135. (No model.)

To all whom it may concern:

Be it known that I, JAN KULHÁNEK, a subject of the Emperor of Austria-Hungary, residing at Prague, Austria-Hungary, have invented certain new and useful Improvements in Provisional or Permanent Walls, of which the following is a specification.

The object of the present invention is to provide new construction of provisional or permanent walls for buildings erected for temporary or permanent use. Such walls preferably consist of narrow parallel sheathings between which at suitable distances studs in the shape of pipes or tubes and preferably of square cross-section are arranged, in which studs vertical rods may be embedded having their upper parts firmly connected by rails.

In the accompanying drawings, forming part of this specification, Figure 1 shows such a wall in perspective view. Fig. 2 is a longitudinal section. Fig. 3 is a cross-section on line C D of Fig. 1. Fig. 4 is a cross-section on line E F of Fig. 1.

In building the improved walls two parallel sheathings *a* and *b* are erected upon a suitable base *m*, of brickwork or other material, at such a distance from each other as to give the desired thickness of the wall or partition. The sheathings are made of slabs or plates of plaster, cork, cement, slags, or other light or fireproof material, according to the requisites. Between the sheathings at suitable distances of from two to five feet and also at the corners and at places where partitions join the walls I erect posts or studs in the form of tubes *n*, preferably made of the same material as the sheathings. The studs *n* are connected with each other and with the plates of the sheathings in any ordinary manner, as by nails, screws, &c. In the tubular studs *n* vertical rods *p* are placed, and then

beton, grout, or mortar is filled in, so as to form compact pillars *q*.

In places where it is necessary for the strength of the building horizontal rails *r* 45 are employed to connect the vertical rods *p*.

The rails and rods, which may be made of metal or any other suitable material, may be connected in any convenient manner—for instance, as indicated in the drawings. 50

The empty spaces between adjacent studs may be filled with any insulating or fireproof material, such as asbestos fiber or sand with or without the addition of mortar, or may be left empty, if desired. 55

Walls erected in the described manner possess great stability, are fireproof and non-heat-conducting, and may be used with advantage in permanent or provisional buildings. 60

Having thus fully described my invention, what I claim as new, and desire to secure by Letters Patent of the United States, is—

1. A wall comprising sheathing forming the inner and outer surfaces, tubular studs between said inner and outer sheathing, mortar filling said studs, and metal rods embedded in said mortar filling, substantially as described. 65

2. A wall comprising sheathing forming the inner and outer surfaces, tubular studs between the inner and outer sheathing, mortar filling said studs, metal rods embedded in the mortar filling, and cross-rails connecting the rods of adjacent studs, substantially as described. 70 75

In testimony whereof I affix my signature.

JAN KULHÁNEK.

In presence of—

ADOLPH FISCHER,
ARTHUR SCHWEZ.
